UNITED STATES PATENT OFFICE.

ALEXANDER W. DREYFOOS, OF MOUNT VERNON, NEW YORK.

PHOTOGRAPHIC DRYING-MACHINE.

1,385,365.

Specification of Letters Patent. Patented July 26, 1921.

Application filed October 28, 1919. Serial No. 333,939.

To all whom it may concern:

Be it known that I, ALEXANDER W. DREYFOOS, a citizen of the United States, residing at the city of Mount Vernon, county of 5 Westchester, State of New York, have invented certain new and useful Improvements in Photographic Drying-Machines, of which the following is a specification.

My invention relates to machines for drying photographic prints.

The principal object of the invention is to provide a machine, embodying an endless conveyer, for continuously drying photographic prints in large quantities.

15 Another object of the invention is to provide the machine with a heated tunnel through which the prints travel and in which they are dried during transit.

A further object is to provide the machine 20 with a ventilating and heat circulating system designed to rapidly and thoroughly dry the prints.

A still further object is to provide novel means for holding and carrying the prints.

25 With these and other objects in view, the invention consists in certain features of construction and combination of parts, all of which will be fully set forth hereinafter and particularly pointed out in the claims.

30 Reference is to be had to the accompanying drawings, forming a part of this specification, in which similar characters of reference indicate corresponding parts in all the figures and in which;

35 Figure 1 is a side elevation of the complete machine, partly in section;

Fig. 2 is a vertical cross-section on the line 2—2 of Fig. 1;

Fig. 3 is a detail perspective view of one 40 of the print holders; and,

Fig. 4 is side view of a section of the conveyer showing prints positioned in the holders.

In order to give a photographic print a 45 glossy finish it is customary to apply the print, by means of a squeegee, face downward upon a japanned tin plate and then to dry the print while in contact with the plate.

The primary purpose of this invention is to

50 provide a continuously operating machine for drying and burnishing the prints. By means of my machine I am enabled to handle large quantities of prints more expeditiously and economically than with any of the drying processes now used in the photographic art.

The operating parts of the machine are mounted on a suitable framework 1 and include a tunnel 2 having means for circulating hot air therein, and an endless conveyer 60 serving to carry the prints through the tunnel.

The photographic prints which the machine is designed to dry are illustrated in Fig. 4 in which A indicates a print applied 65 face downward upon a japanned tin plate B. The plates with prints adhering thereto are successively loaded on the conveyer at the front end of the machine and are then carried through the tunnel whence they are discharged at the rear end with the prints in 70 dried and finished condition.

Mounted upon the main frame 1 is the tunnel 2, which in the present instance is formed of a rectangular shaped casing as 75 shown in Figs. 1 and 2. A series of gas pipes 3, each having a plurality of jets or discharge nozzles extend transversely across the bottom of the tunnel 2 and project through openings in the lower portion of one 80 of the side walls of the tunnel, which openings provide access for lighting the jets. Each of the pipes 3 is fitted with an individual control valve 4 and they are all coupled together by a pipe line 5 connecting 85 with a main 6 and provided with a throttle valve 7. While I prefer to heat the air in the tunnel by means of burning gas jets I desire to have it understood that other heating means may be employed.

Extending lengthwise of the tunnel and mounted at intervals on struts 8 and cross-pieces 9 are a pair of spaced bars or rails 10 which serve as a bed or guide on which the upper reach of the conveyer travels.

Disposed above each of the gas pipes 3 and supported by the members 10 is a curved baffle-plate 11 which acts to direct the current of heated air upward through the spaces between adjacent plates and to provide radiating surfaces. A wire gage screen 12 supported by the cross-pieces 9 extends substantially the full length and width of the tunnel and serves as a protective medium between the gas flames and the conveyer. 100 From the foregoing description it will be seen that the lower portion of the tunnel, that is the portion below the members 10, constitutes a heating system for heating and directing the air current.

105 The upper part of the tunnel is provided with a partition plate 13 supported on

brackets 14 secured to the side walls. The plate 13 is formed with transversely extending slots or openings 15 at intervals throughout its length and serves, in conjunction with the top portion of the tunnel, as a flue for providing proper circulation of the heated air which is discharged through the vent or outlet 16 at the front end of the machine. If desired to operate the drier under artificial draft a suitable exhaust blower (not shown) may be connected to said outlet. To control the draft a slide 17 having openings 18 is provided which slide is operated by means of a handle 19 projecting from the rear end of the machine.

The conveyer comprises a pair of endless chains 20 carried on sprockets 21 and 22 mounted at the front and rear ends of the frame. An adjusting device or screw 23 may be provided for regulating the tension of the chains. A series of print holders, shown in detail in Figs. 3 and 4, are fastened to and extend transversely of the chains. Each holder consists of a bottom member, formed of an angle 24, and two upright members, formed of the angles 25, bolted together. The member 24 serves as a rest for the lower edge of the plate B and is formed with openings, as seen in Fig. 3, to permit of circulation of the heated air. The plate is supported in an inclined position by abutment against the upright members 25 as shown in Fig. 4. This tilted positioning of the plate acts to deflect the ascending current of heated air against the back of the print on the immediately preceding plate and thereby assists in the rapid drying of the print.

The conveyer is driven at a suitable speed to permit of conveniently loading and discharging the same and of drying the prints during transit through the tunnel. The drive is effected by means of an electric motor 26, or other motive power, acting through suitable connecting elements indicated generally by the reference character 27.

While the machine is intended primarily for the purpose of drying photographic prints it may be used for other purposes such for example, as drying photographic plates. Furthermore various changes may be made in the construction herein described

and illustrated without departing from the scope of the invention as defined in the claims.

What I claim as my invention and desire to secure by Letters Patent is:

1. In a machine of the character described, a drying chamber partly open at both ends and having an outlet at its top, a partition extending lengthwise in the upper portion of the chamber and having openings at spaced points, means for adjusting the areas of said openings, heating means disposed in the lower portion of the chamber, an endless conveyer having one of its reaches extending lengthwise through the chamber above the heating means, and a series of inclined plate holders carried on the conveyer.

2. In a machine of the character described, a drying chamber partly open at both ends and having an outlet in its top, a partition extending lengthwise in the upper portion of the chamber and having openings at spaced points, an adjustable closure for said openings slidably mounted on the partition, heating means disposed in the lower portion of the chamber, an endless conveyer having one of its reaches extending lengthwise through the chamber above the heating means, and a series of article holders carried on the conveyer, each including a perforated base rest and inclined back rests.

3. A photographic drying machine, comprising a casing formed with a flue extending lengthwise of its upper portion, a heater disposed in the lower portion of the casing, an endless conveyer having its upper reach mounted to travel lengthwise through the casing above the heater, and a wire gauze disposed between the heater and the conveyer.

4. A photographic drying machine, comprising a casing formed with a flue extending lengthwise of its upper portion, a heater disposed in the lower portion of the casing consisting of series of gas jets and baffle-plates mounted over the jets, an endless conveyer having its upper reach traveling above the heater, and a wire gauze disposed between the heater and the conveyer.

ALEXANDER W. DREYFOOS.
